UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,060, dated September 9, 1902.

Application filed July 29, 1902. Serial No. 117,579. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front elevation.

The leading features of the design consist in a frame the sides and top cross-piece of which have a raised ornamented outer border and a straight unornamented inner edge. At the bottoms of the sides of the frame are urn-like figures from which spring upwardly sprays of foliage, above which garlands of flowers are shown. Extending in diverse directions from the inner upper corners of the frame are scrolls of various forms. The cross-piece is in the shape of a hood with a central figure resembling somewhat a crown in appearance, and extending from the base of this central figure in opposite directions are scrolls

from which spring sprays of foliage. The center or summer front has a plain inclosing border near its outer edges, and within this border is an oval molding. Hung within this molding is a wreath of flowers, flying toward which are shown the figures of three doves. Depending from the same support from which the wreath is suspended and caught up at the sides of the oval molding are garlands of flowers. Garlands of flowers are also shown at the lower corners between the oval molding and its outer border. Below the summer front and extending for the width thereof is a scrollwork open frame.

I claim—

The ornamental design for a fireplace-front as herein described and shown.

In testimony whereof I have hereunto set my hand in the presence of two subscribing witnesses.

THOMAS M. DUDGEON.
